UNITED STATES PATENT OFFICE.

JOSEPH M. KIRBY, OF BOULDER, COLORADO.

PICTURE-PROJECTING MACHINE.

1,294,676.

Specification of Letters Patent. Patented Feb. 18, 1919.

Application filed February 6, 1915. Serial No. 6,433.

To all whom it may concern:

Be it known that I, JOSEPH M. KIRBY, a citizen of the United States, residing at Boulder, county of Boulder, and State of Colorado, have invented certain new and useful Improvements in Picture-Projecting Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to an improvement in picture-projecting apparatus of the general character set forth in my previous Patent No. 915,359, dated March 16, 1909, the said apparatus being adapted to be employed in connection with a phonograph or other sound producing machine, so that the picture exhibition may be directly controlled by and timed in accordance with the reproduction of the phonograph or similar instrument.

20 My present invention relates to certain improvements over the construction disclosed in the aforesaid patent, and the object of the present application is to specifically 30 cover these improvements. One feature of novelty consists in the employment of an independent motor mounted directly upon the picture projecting machine, and forming a part thereof, the said motor being arranged to act in conjunction with the phonograph for operating the screw shaft which carries the dog, whose function is to interrupt the picture-carrying disk during the proper interval, for the display of the picture in alinement with the lenses, during the proper period, in order that the pictures thrown upon the canvas may be in proper 40 synchronism with the words of the phonograph or other talking machine. It has been found in actual practice that the necessary power in the phonograph alone to properly perform this function, is sometimes lacking and the object of this self-contained motor feature of my improvement is to over- 45 come this difficulty. Another feature in connection with this motor is that it is equipped with a fan attachment whereby a current of air through the machine is maintained for cooling purposes, and to keep down the heat 50 55 of the lamp employed in connection with

the projection of pictures, to the proper degree. Without the employment of a cooling feature, the metal casing of the machine would become unduly heated, which, for obvious reasons, is undesirable. Another feature of novelty consists in means for readily disconnecting the power from the dog-carrying screw shaft, whereby the movement of the latter may be interrupted at will. Another feature consists in means for automatically locking the motor for actuating the picture-carrying disk, when the hinged plate carrying the said motor and disk are disconnected from the body of the machine and moved outwardly therefrom, the said locking means being, however, released upon the return of the said plate to its normal or operative position in connection with the operating mechanism of the projecting machine.

25 Still another feature consists in means for adjusting the reflector arranged in the rear of the lamp, whereby the light employed in projecting the pictures may be varied at will.

30 Other features of novelty will be apparent as this specification proceeds.

Having briefly outlined my present improvement, I will proceed to describe the same in detail, reference being made to the accompanying drawing, in which is illustrated an embodiment thereof. In this drawing—

35 Figure 1 is a section taken through my improved machine, approximately on the line 1—1, Fig. 4, certain parts within the casing being shown in elevation.

40 Fig. 2 is a fragmentary detail view of the picture-carrying disk or plate illustrating the face which is provided with teeth which coöperate with the traveling, interrupting dog.

45 Fig. 3 is a fragmentary view of the machine, showing the hinge plate upon which the picture-carrier and its motor are mounted, in two positions, one in full lines and the other in dotted lines.

50 Fig. 4 is a vertical section taken through the machine on the line 4—4, Fig. 1, looking toward the left.

55 Fig. 5 is a horizontal section taken through the machine on the line 5—5, Fig. 4, looking downwardly, or in the direction of the arrow, the governor mechanism being broken away.

Fig. 6 is a fragmentary view of the machine showing the plate upon which the picture-carrier and its motor are mounted, moved away from the body of the machine.

Fig. 7 is a section taken on the line 7, Fig. 4, viewed in the direction of the arrow and showing the means for locking the spring motor 8 against movement.

The same reference characters indicate the 10 same parts in all the views.

Let the numeral 5 designate the main casing of my improved machine, the same containing an incandescent lamp 6, a reflector 7, a spring motor 8 connected in operative relation with a screw shaft 9, which engages a segmental nut 10 carried by a dog 12, which is pivotally mounted and slideable on a spindle 3, its free extremity projecting forwardly into the path of teeth or projections 20 13 formed on a reinforcing disk 14 applied to the picture-carrier 15, the latter, together with the reinforcing disk, being perforated as shown at 16 to receive the extremity 17 of a spindle 18 of a spring motor 19 inclosed 25 within a casing 20 secured to a front plate 21 hinged at its lower extremity as shown at 22, whereby the said plate and motor and the picture-carrier and its connections may be 30 swung away from the main frame and caused to rest upon a forwardly located support 23 carrying a yielding member 24 which the hinged plate directly engages when thrown forwardly out of operative relation with the mechanism within the main casing 5. The 35 spindle 18 of the motor is equipped with a pinion 25 which meshes with a gear 26 fast on a spindle 27 connected in operative relation with a power spring 28. When this spring is wound by applying a key to the 40 spindle 27, it acts upon the gear 26 to operate the spindle 18 through the medium of the pinion 25, whereby the picture-carrier is actuated. This picture-carrier, while loosely 45 engaging the extremity 17 of the spindle 18, is connected to rotate with the spindle by virtue of a pin 29 fast on a disk 30, the said pin passing through a perforation formed in the picture-carrier and its reinforcing disk 14, the disk 30 being made fast on the 50 spindle 18 and being of such size as to give the picture-carrier the necessary support. It should be explained that these picture-carriers may be made mainly of paper, celluloid or other inexpensive material, so far as their 55 outer portions where the pictures are located, are concerned. Located between the pinion 25 and a stationary plate 31 of the spring motor, is a spiral spring 32, which is under tension to move the spindle 18 rearwardly 60 or toward the right, referring to Fig. 1, when the hinge plate is in the operative position, as shown in Fig. 1. In this event, a pin 33 attached to the forward extremity 65 of this spindle, is out of the path of a stop 34 mounted on the plate 31. When, however,

this plate which is normally held in the operative position by a spring 35, is disconnected from its spring and moved forwardly, whereby the extremity 17 of the spindle 18 is disconnected from a sleeve 36 mounted on a spindle 37 within the main casing, the recoil of the spring 32 moves the spindle 18 toward the right, and brings the pin 33 into position to engage the stop 34, thus locking the spring motor 19 against operation and preventing the movement of the picture-carrier. However, as soon as the plate 21 is returned to its normal position, the sleeve 36, acting on the extremity 17 of the spindle 18, moves the latter toward the left and disconnects the pin 33 from the stop, whereby the spring motor 19 is released and acts to rotate the picture-carrier, whereby the teeth 13 of the latter are made to cooperate with the dog 12, as hereinafter more fully explained. 70 75 80 85

The screw shaft 9 carries a small gear 38 which meshes with a pinion 39, the latter also being normally in meshing relation with a relatively large gear 40 of the spring-motor 8 located within the casing 5 and acting to impart rotary movement to the screw shaft, either alone or in conjunction with a phonograph or other talking machine whose spindle 42 is shown coupled with a spindle 2, carrying a pinion 43 also meshing with the gear 40. This last named gear forms one head (see Fig. 4) of a drum 45 which is rotatably actuated through the medium of a coil spring 46 which is connected with the drum at one extremity as 90 shown at 47, and with a spindle 48 at its opposite extremity, the said spindle being journaled in spaced stationary plates 49 and 50. The outer extremity of this spindle 48 is polygonal in cross section as shown at 51, 95 to receive a socket key (not shown), whereby the spring of the motor 8 may then be wound or tightened. This spindle 48 carries a ratchet disk 52 which is engaged by a gravity pawl 53, which, as the spring 46 is 100 wound by turning its spindle 48, locks the spindle against the return movement, as best 105 illustrated in Fig. 1.

The gear 40 further meshes with a pinion 54 fast on a spindle 55 which carries a 110 relatively large gear 56, which in turn meshes with a pinion 57 fast on a spindle 58 journaled in the plate 49 and a plate 59, suitably spaced therefrom. Secured to the spindle 58 is a relatively large gear 60 which 115 meshes with a pinion 61 fast on a spindle 62 journaled in upright arms 63 and 64 of a stationary frame plate 65. This spindle 62 carries a block 66 which is fast on one extremity thereof and to which are attached 120 the adjacent extremities of a number of relatively thin leaf springs 67 which are of considerable length and provided at their centers with weights 68 of such mass as to increase the tendency of the springs to bow 125 130

outwardly under the action of centrifugal force as the spindle 62 is rotated. Splined upon the opposite extremity of this spindle is a block 69 to which the opposite extremities of the governor springs 67 are attached, as shown at 70. To the outer extremity of this block 69 is made fast a friction disk 71, which is engaged by coöperating friction rollers 72 carried by the arms 73 of a yoke 74, whose stem 75 is pivotally connected as shown at 78, with a pin 79 freely slidable in an opening 80 formed in the wall 81 of the casing 5. The pin 79 is provided just at the right of the pivot 78, (see Fig. 4), with an enlargement 82 against which bears one extremity of a spiral spring 83, whose opposite extremity engages the inner surface of the wall 81. This pin has a threaded part 84 which protrudes outwardly beyond the wall 81 and is equipped with a tension nut 85 which is threaded on the pin for regulating the tension of the spring 79. The yoke stem 75 is fulcrumed as shown at 86 upon the upper extremity of the upright 25 part 64 on the frame plate 65.

By virtue of the gearing connection between the gear 40 and the spindle 62, this spindle is rotated very rapidly, whereby the springs 67 are caused to move outwardly, 30 due to centrifugal force. The outward movement of the central portions of these springs causes their extremities adjacent the disk 71 to move inwardly or toward the left (see Fig. 4), whereby the said disk is forced 35 against the coöperating friction rollers 72 carried by the yoke 74, whereby the stem 70 of this yoke is moved toward the right and the spring 79 compressed. By virtue of this construction, the speed of the gear 40 is 40 controlled and regulated.

The spindle 62 projects beyond the upright arm 64 of the frame plate 65, as shown at 87, and is equipped with a fan 88, whereby, during the operation of the machine, air 45 is drawn into the casing 5 through an adjacent opening 89 and forced out of the casing at the top through perforations 90, whereby the heat within the casing incident to the employment of the lamp 6 for picture-projecting purposes, is reduced to such an extent as to render it unobjectionable.

The pinion 39 which transmits motion from the gear 40 to the screw shaft 9 through the medium of a coöperating pinion 55 38, is mounted on a spindle 95 movable in a slot 91 formed in the side wall 92 of the casing, the spindle being actuated by means of a lever 93 fulcrumed as shown at 94 on the outer protruding extremity of the screw 60 shaft 9. Hence, by operating the lever 93, the pinion 39 may be actuated to disconnect it from both the gear 40 and its meshing pinion 38 on the screw shaft, whenever it is desired to break the connection between the 65 motor and the last named shaft.

The lamp 6 is mounted upon a rod 96 whose lower extremity is connected by means of a bolt 97 with two clamping members 98 between which the eye 99 of the rod is located. A wing nut 100 is applied to the 70 threaded extremity of the screw. By tightening this nut on the screw, the lamp-supporting rod may be clamped in the desired position of adjustment. When the lamp is in use, the rod is in the upright position (see 75 Fig. 1) and will be held in this position by means of the nut 100. When it is desired to remove the lamp from the casing 5, the back plate 101 is disconnected by reason of the fact that it is slidably mounted on the body 80 of the casing. As soon as this is done, by loosening the nut 100, the lamp may be thrown out of the casing, as its supporting rod 96 swings on the screw 97. The lamp is mounted upon the rod 96 by means of a 85 clamp 102 which is securely connected with the rod by screws 103 and 104 arranged on opposite sides of the rod. By loosening one or both of these screws, the lamp may be vertically adjusted on its supporting rod 96, 90 since the clamp 102 is part of a clamping ring 105 which encircles the socket 106 of the lamp.

Also mounted on the rod 96 above the clamping member 102, is a support 107 for 95 the reflector 7. This reflector-support comprises an angle member 109 whose lower part 110 consists of a clamp surrounding the upper extremity of the rod 96 and secured in place by a screw 112. The angle member 100 also includes a part 113 extending at right angles to the rod and coöperating with a part 114 to permit the movement of the reflector toward and away from the lamp. These two parts 113 and 114 are slotted to 105 receive a screw 115 which is held in place by means of a nut 116. By loosening this nut the part 114 may be moved to cause the reflector to occupy a position nearer or farther from the lamp, as may be desired. 110 Furthermore, by loosening the screw 112, the clamp 110 may be moved rotatably upon the rod 96, whereby the position of the reflector may be changed to harmonize with the requirements in any particular case. Connected by means of a screw 118 with the outer extremity of the part 114 of the angle member, is an upwardly extending arm 117 which is slotted as shown at 119, to receive a screw 120 which is rigidly connected with 115 the reflector 7 by means of a nut 122. By reason of this construction, the reflector may be adjusted to regulate the light to conform to all possible conditions in a projecting machine.

When the machine is in use, the lamp 6 is arranged in the rear of the alined lenses 123 and 124. The lens 123 is mounted on the front plate 125 of the main casing by means of screws 126; while the lens 124 is 130

mounted on the hinged plate 21 carrying the spring motor 19 for actuating the picture-carrier, as heretofore explained.

- The spring 35 which retains the plate 21 in operative relation with the picture-projecting mechanism within the main casing, is of the leaf type, and is provided with a recess 127 which is adapted to receive the upper extremity of the plate (see Fig. 1).
 5 10 This spring projects outwardly beyond the plate as shown at 128, whereby it may be lifted sufficiently to release the plate whenever desired. This part 128 is curved upwardly, so that the plate 21 will automatically assume its normal position when given the proper movement in the direction of the main casing, as will be readily understood.
 15 When the plate 21 is in the position shown in Fig. 1, whereby it coöperates with the picture-projecting mechanism, the spindle 18 is forced forwardly to disconnect the pin 33 from the stop 34, as heretofore explained. The sleeve 35 which the rear extremity of the spindle engages, is arranged to receive 20 its spindle 37, whose forward extremity engages a spiral spring 129 located within the sleeve and which is of greater strength than the spring 32 mounted on the spindle 18, and whose tension must be overcome in order 25 that the forward thrust of the spindle 18 may occur, to disconnect the pin 33 from its stop 34, as heretofore explained. The rear extremity of the spindle 37 is threaded and engages a threaded perforation in a bracket 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

ment with the two lenses, so that it may appear upon the canvas for a corresponding period. It is evident that by tightening or loosening the nut 85 of the pin 79, the tension of the spring 83 may be regulated to accurately control the speed of the motor 8, in order to cause its movement to properly actuate the picture-carrier to harmonize with the piece reproduced upon the phonograph and illustrated in the pictures mounted on the picture-carrier. It should be explained that each picture-carrier will have its teeth or projections 13 which are adapted to be engaged by the dog 9, as heretofore explained, arranged with special reference to the piece which the pictures of the carrier illustrate. Hence, the number of picture-carriers will correspond with the number of musical pieces with which the picture-projecting machine is to be employed.

While it will often be convenient to use my improved picture-projecting machine disconnected from the phonograph but in synchronism therewith, as heretofore explained, it may also be directly coupled with the phonograph, as shown in Fig. 4, in which the spindle 42 is operated by the motor of the phonograph, and is coupled to rotate with the spindle 2 of the picture-projecting machine. In this event, the two motors will coöperate, giving the necessary power under all circumstances for actuating the picture-carrier-interrupting dog, as heretofore explained.

While the picture carrier 15 as illustrated in the drawing, is reinforced by a disk 14, this carrier may be made integral and teeth 13 punched out of the material of which it is composed or otherwise formed thereon or attached thereto, as may be desired.

In order to lock the motor 8 against movement whenever desired, I may employ a brake comprising a disk 132 which is fast on the outer exposed extremity 133 of the governor shaft 62, the said disk being arranged to be acted on by a shoe 134 which is actuated by an eccentric cam 135 mounted on a spindle 136, the spindle being journaled or swiveled in a bearing 137. The outer extremity of this spindle is equipped with a relatively large milled head 138. By properly adjusting this spindle, the shoe may be separated from the periphery of the disk 132 (see Fig. 7). Again, when it is desired to cause the shoe to engage the peripheral face of the disk, for locking the motor against movement, the spindle may be adjusted to cause the cam 135 to force the shoe downwardly against the face of the disk, whereby sufficient friction will be produced to lock the disk and consequently, the governor spindle 62, as well as the entire spring motor mechanism against movement. When it is desired to start the motor, it is only neces-

sary to release the disk by the proper adjustment of the shoe.

Having thus described my invention, what I claim is,—

- 5 1. In a picture-projecting machine, the combination with a suitable casing and picture-projecting mechanism located therein, of a plate connected with said casing to move toward or away from the same, a picture-carrier mounted on said plate, a motor also mounted on said plate for actuating said carrier, means for automatically locking the motor against movement as the said plate is moved away from the picture-projecting mechanism, and means for releasing the motor as it is moved into coöperative relation with said mechanism.
- 10 2. In a picture projecting machine, the combination with a suitable casing and projecting mechanism mounted therein, of a plate connected with the casing to move toward or away from the same, a picture carrier mounted on the plate, a motor also mounted on the plate for actuating the carrier, and means for automatically locking the motor as the plate is moved away from the projecting mechanism.
- 15 3. In a picture projecting machine, the combination with a casing and projecting

mechanism, of a picture carrier connected 30 with the casing, means for imparting movement to the carrier, a dog for intermittently interrupting the carrier, means for actuating said dog, a motor mounted within the casing, a connection between said motor and 35 said dog-actuating means including a gear movably mounted to break said connection.

4. In a picture projecting machine, the combination with a casing and projecting mechanism, of a picture carrier connected 40 with the casing, means for imparting movement to the carrier, a dog for intermittently interrupting the carrier, a screw shaft for operating said dog, a motor mounted within the casing, a connection between said motor 45 and screw shaft including a gear on the motor and a gear mounted on an oscillatory axis and meshing with the motor gear and adapted to be withdrawn from said motor gear by oscillatory movement, and means 50 for oscillating said gear.

In testimony whereof, I affix my signature in presence of two witnesses.

JOSEPH M. KIRBY.
